Attorney.

UNITED STATES PATENT OFFICE.

FRANK FOSTER, OF KANSAS CITY, MISSOURI.

CREASE RETAINER.

Application filed July 19, 1926. Serial No. 123,567.

My invention relates to means for retaining the longitudinal crease in the front and rear portions of trousers so that it will not be necessary to press the latter as frequently as heretofore for the purpose of presenting a neat appearance.

A further object of the invention is to reinforce the trouser legs so that they will not be so apt to bag at the knees, or become wrinkled. 10 In order that the invention may be fully understood, reference will now be had to the accompanying drawing in which:

Fig. 1 shows a side elevation of a pair of trousers, partly broken away to show the 15 crease retaining means.

Fig. 2 is a detail of one of the crease retaining elements.

Fig. 3 is a detail of one form of means for holding the crease retaining element in place. 20 Fig. 4 is a fragmentary section on line 4-4 of Fig. 1.

Fig. 5 is a fragmentary cross section of a modified form in which the crease retaining element is held in place by a suitable adhesive substance. 25

Fig. 6 is a fragmentary cross section of a modification in which the crease retaining element is sewed in place.

Referring in detail to the different parts, 30 2 designates a crease retaining element which may consist of any suitable material, such for instance, as a cord or a strand of wire.

4 designates a strip of fabric or other suitable material for holding the crease retaining 35 element 2 in place.

In practice each leg of the trousers A may be provided at their front portions only with the crease retaining elements 2, or they may be equipped at both front and back as shown 40 by Fig. 1.

In the preferred embodiment of the invention each leg of the trousers is equipped at front and back, at the points where they are usually creased longitudinally when pressed, 45 with the crease retaining elements 2. Said

crease retaining elements 2 may extend from the lower portion B of the trousers to the waist band C, or they may be as much shorter as desired. After being located at the proper place the retaining elements 2 have their ends 50 6, which are preferably coiled or folded as shown by Fig. 2, stitched to the trousers after which said crease retaining elements 2 are further secured by the strips 4, which are placed inside of the trousers and secured over the retaining elements 2 with a suitable adhesive substance. The strips 4 are preferably long enough to entirely cover the crease retaining elements 2 and have their ends 8 enlarged to cover the folded ends 6 of the retaining elements 2. 55

In the modified form disclosed by Fig. 5, the strips 4 are dispensed with and each crease retaining element 2^a is held in the respective leg D with a suitable adhesive substance. 60

In the modified form disclosed by Fig. 6, each crease retaining element 2^b is secured in place in the respective leg E by stitching 10.

When a pair of trousers are reinforced in 70 any of the different ways above pointed out, it is apparent that when pressed they will retain the resultant creases for a much longer period of time than trousers not so equipped. It is also apparent that the equipped trousers 75 are not so liable to bag at the knees or become wrinkled.

Having thus described my invention, what I claim and desire to secure by Letters Patent is:

In combination with a pair of trousers, 80 crease retaining cords extending longitudinally of the trouser legs and folded at their ends, said folded ends being sewed to the trousers and strips of suitable material for holding said cords in place and provided at their ends with enlargements for covering the folded ends of said cords. 85

In testimony whereof I affix my signature.
FRANK FOSTER.
